UNITED STATES PATENT OFFICE.

HUGH G. TAYLOR, OF BUHL, IDAHO.

ROAD-GRADER.

1,142,381.

Specification of Letters Patent. Patented June 8, 1915.

Application filed August 29, 1912, Serial No. 717,712. Renewed July 14, 1913. Serial No. 779,005.

To all whom it may concern:

Be it known that I, HUGH G. TAYLOR, a citizen of the United States, residing at Buhl, in the county of Twin Falls and State 5 of Idaho, have invented a new and useful Improvement in Road-Graders, of which the following is a specification.

The object of my invention is to provide a road grader which is adapted to be mounted upon an axle or other suitable supporting part of a vehicle and which can be detached at will. It is desirable that a grader of this character shall be inexpensive, simple, adjustable, and effective in operation and also 10 adapted for use on either side of a road. These features are accomplished by my invention in an efficient and effective manner and the device is adapted to improve the condition of the road so that chuck holes are 15 not formed, the road being kept smooth and oval in shape.

In the accompanying drawing forming part of this specification Figure 1 is a plan of the running gear of a wagon showing 20 my improved grader applied thereto; Fig. 2 is a side elevation and Figs. 3 and 4 are details showing the construction by which the disk may be held in selected position upon its support.

30 In the drawings A indicates the running gear of a wagon having a front axle 2, back axle 3 and wheels 4, said front axle being mounted upon king bolt 5 so as to turn freely below the front bolster 6.

35 B indicates my improved grader which has a drag C and an earth working device D in the form of a disk in advance of the drag, said parts being adapted to coöperate and level the surface of the road over the 40 track on the wheels on either side of the running gear.

A frame is provided upon which the drag or scraper and disk are carried, said frame being of triangular shape and formed by 45 two arms 7 and 8, said arms forming two sides of a triangle with the apex thereof directed rearwardly from the front axle 2. The ends of the arms 7 and 8 are detachably hinged by bolts 9 and 10 to the axle 2 and 50 the arm 7 is a tube into which an extension rod 11 is adapted to telescope to provide extensible adjustability for the drag and disk

as regards the frame which carries them. Any suitable means may be employed for detachably securing the arms 7 and 8 to the 55 axle.

The extension rod 11 is held in the tube 7 by split pins 12 passing transversely through said parts, said pins also serving to prevent rod 11 from turning in its support. Upon the end of arm 11 a disk D is mounted by means of a short shaft 13 which is journaled to the disk and adjustably secured to the end of the arm 11 by means of the bolt 14 passing vertically through enlarged horizontal flat portions on the adjacent ends of rod 11 and shaft 13. The impinging surfaces upon said enlarged portions of the ends of the extension rod 11 and shaft 13 are serrated at 15 so that when the 70 bolt 14 is tightened by its lock nuts the shaft 13 is held rigidly in radially adjusted position. This radial adjustability of the disk allows the disk to be set while in upright position at any angle desired across the 75 surface of the road to produce the desired width of cut. The disk is also held in longitudinally selected position upon the shaft 13 between collars 16 which are secured to said shaft by set bolts 17. Thus greater range of 80 adjustability is provided for the disk whereby it may be so placed over that portion of the road as to most effectively loosen and direct the loosened earth inwardly and upwardly over the road surface. The extensible rod 11 also carries a pair of rearwardly extending supports 18 upon which the drag 85 C is rigidly mounted, said drag consisting of a vertically disposed plate 19 extending back from the disk and inclining rearwardly 90 over the surface of the road in position to smooth the surface and direct the earth inwardly and upwardly to form a smooth oval shaped road.

The arms 18 are hinged upon the rod 11 95 by supports 20 and pintle bolts 21 passing through the supports and arms and permitting the drag to be raised independent of the frame B. When desired the drag may be raised out of operative position by a 100 chain 22 independent of the frame, or the frame and drag may be raised together by the chains 22 and 23. These chains are illustrated passing over sheaves 24 on the side

of the body 25 of the vehicle and their links fastened to hooks 26 on the body. To hold the frame B and drag in superior position it is only necessary to draw the chains forward 5 and secure their links over the hooks.

By mounting the frame supporting the disk and scraper on the front axle the device is made to follow in the track of one of the front wheels around curves. It is obvious 10 the device will operate on one side of a road when the vehicle is traveling in one direction and on the other side when returning. The device may also be designed for use either on the right or left hand side of a road when the vehicle is advancing in one direction. The parts are made of sufficient weight to urge the earth working device and scraper in effective engagement with the ground for grading purposes. Should 15 either the scraper or disk meet with an obstruction it will mount and ride over it independent of the other. The entire device may be quickly and easily attached to or detached from the front axle. It is further obvious 20 that the device may be fastened in a similar manner as described to the rear axle or other part of the vehicle with substantially equal effectiveness and where the term "front axle" is employed, I wish it understood 25 that the rear axle should be construed as the full equivalent thereof.

In accordance with the patent statutes I have described the principles of operation of my invention together with the apparatus 30 which I now consider to represent the best embodiment thereof but I desire to have it understood that the construction shown is only illustrative and that the invention can be carried out by other means and applied 35 to uses other than those above set forth within the scope of the following claims.

Having described my invention, what I claim as new and desire to protect by Letters Patent is:—

45 1. In combination with the running gear of a vehicle having an axle, a frame hinged to said axle to swing up and down, said frame having a tube in which a rod is adapted to telescope to lengthen or shorten said 50 frame, means for fixing said rod in different positions in said tube, a rotatable cutter freely journaled upon said rod and adapted to follow in the path of one of the wheels of the running gear and to revolve in a 55 plane at an angle across the line of travel of said wheel, and a scraper blade supported by said frame and movable up and down freely back of said cutter and at a rearwardly inclined angle to collect the trimmings cut by said cutter.

60 2. In combination with a vehicle having a running gear, a frame hinged to a part of said vehicle and adapted to swing up and down, an extensible arm secured to said frame and extending back of one of the

wheels on one side of the running gear, an earth working device journaled freely upon the outer end of said arm and a scraper hinged to said arm and extending inwardly and following said earth working device, 70 said scraper being adapted to swing up and down.

3. In combination with the running gear of a vehicle, a frame detachably secured to a part of said vehicle, an arm extensibly secured to said frame and projecting back of one of the wheels on one side of said running gear, an earth working device mounted on the outer end of said arm and a scraper hinged to said arm and extending inwardly 75 and following said earth working device, 80 said scraper being adapted to swing up and down freely.

4. In combination with a vehicle having a frame hinged to a part of said vehicle and extending rearwardly, an arm extensibly secured to said frame and projecting back of one of the wheels on one side of said running gear, a rotary cutter secured to the outer end of said arm and a scraper hinged to said arm and extending inwardly and rearwardly and following said cutter, said scraper being adapted to swing up and down freely, means for raising said scraper 90 and means for raising said frame with the rotary cutter which it carries.

5. In combination with the running gear of a vehicle, a frame hinged to an axle thereof and extending rearwardly, an arm extensibly secured to said frame and projecting back of one of the wheels on one side of said running gear, a shaft pivotally secured to the end of said arm and adapted to swing in a substantially horizontal plane, means for holding said shaft in fixed position as regards its pivot, an earth working device mounted upon said shaft, a rearwardly extending frame hinged to swing up and down on said arm and carrying a scraper blade on its rearward end following said earth working device.

6. In combination with a vehicle having a running gear, a frame hinged from a part of said vehicle to swing up and down and having its free end adapted to trail after one of the wheels of said running gear, a disk cutter carried by the free end of said frame and adapted to cut down high places at the sides of a rut immediately following said wheel and a scraper carried by the free end of said frame and dragging back of said disk and adapted to level the loosened earth over said rut.

7. In combination with a vehicle having a running gear, a frame hinged to a part of said vehicle and having its free end adapted to trail and move freely up and down, an earth working device mounted on the free end of said frame and adapted to cut down high places at the sides of ruts in a road and a

scraper hinged to the free end of said frame and dragging back of said earth working device, said frame extending laterally and said scraper being adapted to move freely up and down upon said frame so as to level loose earth following said earth working device.

In testimony whereof, I have signed my name to this specification, in the presence of two subscribing witnesses.

HUGH G. TAYLOR.
